UNITED STATES PATENT OFFICE.

HERMANN LEMP, OF LYNN, MASSACHUSETTS, ASSIGNOR TO GENERAL ELECTRIC COMPANY, A CORPORATION OF NEW YORK.

FUEL-PUMP.

1,112,299.

Specification of Letters Patent. Patented Sept. 29, 1914.

Application filed August 23, 1912. Serial No. 716,669.

To all whom it may concern:

Be it known that I, HERMANN LEMP, a citizen of the United States, residing at Lynn, county of Essex, State of Massachusetts, have invented certain new and useful Improvements in Fuel-Pumps, of which the following is a specification.

This invention relates to pumps for supplying liquid fuel to internal combustion engines, and more especially to that type of engine wherein the compression of the air in the cylinder produces so high a temperature that the fuel charge is ignited when it is injected into the cylinder.

15 The object of the invention is to provide an improved mode of regulating the pump which delivers the fuel to the cylinder or cylinders of the engine, so that the quantity delivered will vary with the load. To this end a pump is used in which the plunger, or each of the several plungers, displaces a fixed volume of fuel at every stroke, but the suction valve or valves can be held open for a longer or shorter time during the forcing 25 stroke of the pump so that a portion of the fuel can find its way back to the supply tank instead of going to the engine. The suction valve or valves is or are controlled by the speed governor of the engine, so that 30 the fuel actually delivered to the cylinder or cylinders is directly dependent upon the speed, being increased when the speed drops off, and vice versa.

35 The present invention resides in the special devices for effecting this control, which is accomplished electrically.

In the accompanying drawings, Figure 1 is an elevation of a portion of an internal combustion engine embodying my invention; Fig. 2 is an elevation at right angles to Fig. 1; Fig. 3 is a section of the pump; Fig. 4 is a section of the variable contact switch on the line 4—4, Fig. 2; and Fig. 5 is a diagram of circuits.

45 It is assumed that the engine 1 illustrated has three cylinders, each supplied with liquid fuel by its own pump, the several plungers 2 being secured to a cross-head 3 which is reciprocated by a rod 4 and eccentric 5. A shaft 6 carries the eccentric and is provided with a gear 7 which meshes with another gear 8 on the upright shaft 9 which drives the speed governor 10.

55 The pumps are all alike, so that a description of one will suffice for all. The

plunger 2 works through a stuffing box 11 in the top of the casing 12. A check valve 13 prevents any return of the fuel forced into the delivery pipe 14, which runs to the cylinder. The suction valve 15, which controls the supply pipe 16, opens downwardly against the tension of a spring 17. Its stem 18 extends up through the top of the casing in line with an arm 19 on a rock-shaft 20. A set screw 21 in said arm determines the 65 point in its movement where it comes in contact with the valve stem.

On the rock-shaft 20 is an arm 22 to which is pivoted the movable core 23 of a solenoid 24. A variable contact switch controlled by the speed governor operates to energize this solenoid at the proper times to pull down the rock-arm 19 and hold the suction valve open. The switch preferably comprises a cylinder 25 mounted on the shaft 6 and composed of conducting and non-conducting segments *a*, *b* united on a diagonal plane. Two brushes 26, 27 stand side by side, one bearing on a collecting ring on the shaft 6 and the other on the surface 80 of the cylinder 25. Said cylinder and the brush 27 are relatively movable; preferably by means of the following construction: The brushes are secured to hubs 28, 29, which are mounted on but insulated from a short shaft 85 30 supported in the arms of a fork 31 on a bracket secured to the frame of the engine. The hub 28 is stationary, but the hub 29 carrying the brush 27 can slide along said shaft 30, which is preferably squared to 90 keep the brush always in close contact with the cylinder 25. A link 32 is pivoted to the hub 29 and to an arm 33 on a rock-shaft 34, which has another arm 35 connected by a rod 36 and a lever 37 with the sliding collar 38, which is caused to rise and fall on the shaft 9 by the movement of the governor weights.

The two brushes 26, 27 are connected by wires 39, 40 with the terminals of the solenoid 24. A battery 41 or other source of current is connected to the wire 40 and to the middle point of said solenoid, which is preferably differentially wound; though a simple solenoid wound from end to end could be used if desired. The differential winding prevents sparking at the brushes.

The operation of the device is as follows:—The pump plungers displace a constant quantity of fuel at each stroke. If the 110

load is heavy, the governor keeps the brush 27 on that part of the cylinder 25 where the angular width of the conducting segment *a* is short, and consequently the length of time 5 of energization of the solenoid 24 will be short, so that during most of the forcing stroke of the pump, the suction valves will remain closed and the greater part of the fuel will be sent to the engine. But if the 10 load drops, and the engine speeds up, the governor will slide the brush 27 over to the left in Fig. 2, so that a wider part of the conducting segment is engaged, and the circuit is kept closed during a greater portion 15 of the forcing stroke. This means that the energization of the solenoid lasts longer, and consequently the depression of the suction valves is maintained for a longer portion of the forcing stroke, so that more of the fuel 20 is allowed to return to the supply tank and less goes to the engine, thereby slowing it down.

In accordance with the provisions of the 25 patent statutes, I have described the principle of operation of my invention together with the apparatus which I now consider to represent the best embodiment thereof; but I desire to have it understood that the 30 apparatus shown is only illustrative, and that the invention can be carried out by other means.

What I claim as new and desire to secure by Letters Patent of the United States, 35 is:—

1. The combination with an internal com-

bustion engine, of a fuel pump having a constant stroke, a suction valve therefor, a solenoid for holding said valve open, a rotary switch having a conducting segment of varying width, a relatively movable brush 40 coöperating therewith, and a speed governor adapted to vary the point of contact between said switch and said brush.

2. The combination with an internal combustion engine, of a fuel pump having a constant stroke, a suction valve therefor, a solenoid for holding said valve open, a rotary switch operating in synchronism with 45 said pump and consisting of a cylinder having a conducting segment of varying width, 50 a brush movable along said cylinder, and a speed governor adapted to move said brush.

3. The combination with an internal combustion engine, of a fuel pump having a constant stroke, a suction valve therefor 55 having an upwardly-extending stem, a rock-arm to push said stem downwardly and open said valve, a solenoid to actuate said arm, a rotary switch operating in synchronism with said pump, and a speed governor 60 adapted to vary the length of time said switch closes the circuit of said solenoid during the forcing stroke of said pump.

In witness whereof, I have hereunto set my hand this nineteenth day of August 65 1912.

HERMANN LEMP.
